UNITED STATES PATENT OFFICE.

PERRY M. SHEPARD, OF CHICAGO, ILLINOIS.

DESIGN FOR A COMBINED SOAP-DISH AND TOOTH-BRUSH HOLDER.

46,975.

Specification for Design.

Patented Feb. 16, 1915.

Application filed November 13, 1914. Serial No. 872,022. Term of patent 7 years.

To all whom it may concern:

Be it known that I, PERRY M. SHEPARD, a citizen of the United States, residing at Chicago, in the county of Cook and State of Illinois, have invented a new, original, and ornamental Design for a Combined Soap-Dish and Tooth-Brush Holder, of which the following is a full, clear, and exact description, reference being had to the accompanying drawing, forming a part hereof.

In the drawing: The drawing represents a perspective view of said combined soap-dish and tooth brush holder.

The drawing shows a combined soap-dish and tooth-brush holder consisting wholly of wire; the soap-dish consisting of criss-cross longitudinal and transverse wires with their ends bent upward in the same manner and to a corresponding extent, and terminating in eyes. The eyes of the criss-cross wires at the end, and at the front of the soap dish encircle the front and end stretches of a longitudinally disposed rectangular wire frame, and the eyes on the rear ends of the transverse wires are looped around and en-

circle a longitudinally disposed wire-bar the ends of which encircle and are supported by the end stretches of the rectangular edge-frame of the dish. The wires constituting the end stretches of this rectangular edge frame extend horizontally to the rear of the wire bar of the dish and then vertically upward to a corresponding extent and their upper ends are united by a horizontal stretch of wire, which is provided with upwardly extending loops, and said vertical portions of the end-stretches of the rectangular frame are connected by a horizontal wire that is provided with forwardly projecting loops between its ends.

What I claim is:

The ornamental design for a combined soap-dish and tooth-brush holder, as shown and described.

In witness whereof I have hereunto set my hand this 21st day of October, 1914.

PERRY M. SHEPARD.
